UNITED STATES PATENT OFFICE.

HERBERT E. RIDER, OF BROOKLYN, NEW YORK, ASSIGNOR TO LOUIS LEVIEN, OF NEW YORK, N. Y.

PROCESS OF GAS GENERATION.

1,218,470.

Specification of Letters Patent.

Patented Mar. 6, 1917.

Application filed December 26, 1914. Serial No. 879,205.

To all whom it may concern:

Be it known that I, HERBERT E. RIDER, a citizen of the United States, residing at Brooklyn, in the county of Kings and State 5 of New York, have invented certain new and useful Improvements in Processes of Gas Generation; and I do hereby declare the following to be a full, clear, and exact description of the invention, such as will enable 10 others skilled in the art to which it appertains to make and use the same.

This invention relates to gas generation from oil and provides a process in which a spray of oil is gasified and then subjected to 15 oxidizing treatment so that the same may be used in an internal combustion engine without leaving any carbon precipitate in the cylinders of said internal combustion engine.

A further object of this invention is the 20 provision for the treatment of said gasified vapor by amalgamation with the vapor to enable the dilution of the final gas.

Further objects will be apparent from the 25 following specification, appended claim and drawing in which,

Figure 1 is a vertical sectional view through a device constructed in accordance with an apparatus for carrying out this process and

30 Fig. 2 is a similar view of a portion thereof enlarged.

This invention provides for a process by which kerosene or the like may be vaporized or gasified to enable said vapor or gas being 35 fed to an internal combustion engine of the usual type. It is clearly seen that an apparatus employing the elements to be described is capable of operation by pressure or suction and when considered in connection with 40 an internal combustion engine, the suction established by the piston may be employed in actuating this apparatus.

Referring to the drawings of this application in which similar reference numerals 45 indicate similar parts, there is shown a fitting 10 to which a sleeve 11 may be attached in any desired manner and within the sleeve 11 is a tube 12 having a flaring upper portion 13, terminating in a flange 14 by 50 which said tube is clamped between the sections 10 and 11. The tube 12 is provided at intervals with baffle units 15 which may be formed by nesting a number of small tubes. The sleeve 11 has its lower end attached to a 55 casing 16 in which the lower end of the tube

12 terminates. The casing 16 is provided with a flange 17 upon which a screen 18 bears and upon the screen 18 is a sleeve 19 which supports a screen 20 of the same type as the screen 18. 60

The casing 16 contains a body of oil which is maintained at a desired level by the float 21 supported by the arm 22 which is fulcrumed as at 23 to the casing so that the yoke 24 will actuate the weighted valve stem 65 25 when the supply of oil becomes consumed to allow a supply through the tube 26 to replenish the consumed portions.

A tube 27 is connected to the casing 16 in any desired manner and leads to the fitting 70 28 to which a series of tubes 29 are connected and each of these tubes is provided with an air inlet 30 by which suction formed in the fitting 10 permits air to enter the fitting 10 through the jet 31 and siphon oil through 75 the tubes 29 from the casing 16. As the oil is sprayed through the jet 31, the jet is confined in the fitting 10 and it is ignited as by a spark plug 32 connected to a source of electrical supply in the usual manner. The 80 air admitted through the air inlets 30 is insufficient to support complete combustion and as it is necessary to ignite the vapor, an air valve 33 is provided by which the controlled quantities of air may be admitted. 85 This valve carries an adjustable thumb nut 34 to allow the proper adjustment being made with the spring 35 so that the valve 33 will not admit air in greater quantities than is really necessary. 90

As in use with internal combustion engines, it frequently occurs that the load on the engine varies and likewise the speed of the engine varies, it is necessary that provision be made to check the generation of 95 gas at certain times and to increase the generation of gas at other times. In my apparatus, I provide a valve 36 slidable in the sleeve 37 and controlled by the spring 38 together with the adjusting nuts 39, by which 100 the suction in the fitting 10 causes said valve to slide to open or close one or more of the jets 31 as the case may require. It is apparent that when the load on the engine is light and it tends to race, the suction in the fitting 10 is increased which would tend to generate richer gas but in this event the valve 36 will be slid to close some of the jets 31 and thereby reduce the quality of the gas generated which in turn reduces the speed 110 115

of the engine or as is apparent, maintains a uniform speed of the engine to likewise maintain a uniform suction.

The sleeve 11 is provided with a boss 40 to which an elbow 41 is connected and this elbow has the usual flange 42 formed thereon by which it may be connected to the manifold of an internal combustion engine not shown. This elbow is provided with an air valve 43 slideable in a spider 44 formed in the nipple 45. The valve stem is threaded and provided with the adjusting nuts 46 by which pressure on the spring 47 may be varied and manipulation of the valve 43 to 10 overcome the action of the spring 47 is had by means of the lever 48 which is fulcrumed as at 49° and to which the rod 50 leading to any desired point of operation is connected.

When it is desired to main a supply of 20 rich gas against the action of the movement of the valve 36, manipulation of the rod 56 will cause the lever 57 to swing and engage against one of the nuts 39' and hold the valve in the position which allows all of the jets 25 31 to remain active. The lever 57 may be supported by a bracket 55 as shown.

The operation of this device may be clear in view of the foregoing, but the following is intended to more fully describe the generation of gas with an apparatus of this 30 type. The spark plug will be connected through the usual source of supply and the supply of oil established to sufficiently fill the casing 16. Then upon starting an internal combustion engine in the usual manner, a suction would be established through the elbow 41, within the sleeve 11, casing 16, tube 12 and fitting 10, at which time the ingress of air through the inlets 30 will inject 35 oil through the tubes 29 and spray the same through the jets 31. The adjustment of the valve 33 is such as to cause the injection of the spray into the fitting 10 before air is admitted past the valve 33. During the intermittent or constant suction, the oil is sprayed into the fitting 10, the valve 33 admits a proportioned amount of air, the spark plug 32 ignites this spray to set up the combustion thereof, but before the elements are 40 consumed the gases are passed through the tube 12 and the baffle units 15 when the flame is smothered and in passing through the tube 12, the gaseous products of partial combustion are allowed to expand and properly 45 mix. In passing from the tube 12, these gaseous products of combustion are impinged against the oil in the casing 16 when said gas absorbs part of this oil and amalgamates so to speak, with the gas in the casing 16 and passes through the screens 18 and 50 into the sleeves 11, from where it is

drawn through the elbow 41. When it is desired to dilute this gas to affect the explosive qualities thereof, air may be admitted past the valve 43 which mixes with the 55 gas and dilutes it in proportion to the volumes of air admitted.

In the generation of gas by this process and with this apparatus, I find that in impinging the products of combustion against 70 a comparatively cool body of oil, this gas assumes the particular characteristic which may be termed carbureted so that when same is subsequently admitted to a cylinder and fired, the by-products in said gas are discharged from said cylinders with the burnt gases and no precipitate forms in the cylinder. Also I find that by impinging said gas against a comparatively cool body of oil, a much richer gas is produced and one 80 which may be diluted by the admixture of air, which is an impossibility with the gas taken directly from the tube 12.

The generation of gas by smothering an unconsumed vapor is admitted to be old, but 85 the treatment of such gas as shown and described produces a new type of gas applicable to the usage heretofore described.

Modifications may be made within the scope of this invention by changing the relative positions and proportions of the several parts shown as well as other modifications apparent to those skilled in the art, but the drawings are submitted for illustrative purposes only. 95

Having thus described my invention I claim:

The process of gas generation comprising the use of suction formed by an engine to atomize oil by ingress of air currents through 100 jets connected to a source of oil supply, mixing air with the finely divided particles of oil, ignition of the mixture of air and oil vapor, smothering the flame by passage of the partly consumed gas through a restricted 105 passage, thoroughly mixing the gas by passage through fine passages and mixing chambers, between sets of individual passages, enriching said gas by impinging it against a static body of oil in which evaporation of particles of said oil occurs, and further mixing the enriched gas by passage 110 through screens of fine mesh to break up individual currents, and the treatment of said gas by the admixture of air in proportions 115 to vary the richness thereof.

In testimony whereof I affix my signature in presence of two witnesses.

HERBERT E. RIDER.
